UNITED STATES PATENT OFFICE.

SAMUEL C. UPHAM, OF PHILADELPHIA, PENNSYLVANIA.

DESIGN FOR BOTTLE.

Specification forming part of Design No. 7,864, dated November 17, 1874; application filed September 30, 1874
[Term of Patent 7 years.]

To all whom it may concern:

Be it known that I, SAMUEL C. UPHAM, of Philadelphia, Pennsylvania, have invented a Design for the Body of a Bottle, of which the following is a specification:

The body A of the bottle, as shown in the accompanying drawing, is made in the shape of a bell, from the top of which projects the neck a, the latter being either plain, as shown, or ornamented, as the taste of the manufacturer may suggest; my design being restricted to the body of the bottle, exclusive of the neck, but inclusive of a mark, x, which ex-

presses the condition of the crack in the bell of Independence Hall, Philadelphia.

I claim—

The design for the body of a bottle with a mark, x, as described and illustrated in and by the accompanying drawing.

In testimony whereof I have signed my name to this specification in the presence of two subscribing witnesses.

SAMUEL C. UPHAM.
